(57) **CLAIM**

The ornamental design for adjustable weed cutting tool, as shown and described.

DESCRIPTION

FIG. 1 is a perspective view of the top, one side and the front of the adjustable weed cutting tool according to one embodiment of my new design;

FIG. 2 is a front view thereof;

FIG. 3 is a back view thereof;

FIG. 4 is a right side view thereof; and,

FIG. 5 is a left side view thereof.

The tool is shown with illustrative breaks. The portions between the break lines form no part of the claimed design.
